UNITED STATES PATENT OFFICE.

GEORGE EDWARD FIGG, OF MONTREAL, QUEBEC, CANADA.

BUCKLE AND BAND.

1,088,890.

Specification of Letters Patent.

Patented Mar. 3, 1914.

Application filed March 8, 1912. Serial No. 682,500.

To all whom it may concern:

Be it known that I, GEORGE EDWARD FIGG, a subject of the King of Great Britain, and a resident of 715 Wellington street, in the 5 city of Montreal, in the Province of Quebec, in the Dominion of Canada, have invented certain new and useful Improvements in Buckles and Bands; and I do hereby declare that the following is a full, clear, and 10 exact description of the same.

The invention relates to improvements in a buckle and band, as described in the present specification and illustrated in the accompanying drawings that form part of the 15 same.

The invention consists essentially of the novel construction and arrangement of the buckle and band, more fully disclosed hereinafter.

20 The objects of the invention are to devise buckle and band particularly applicable as a necktie holder for double collars, to provide a very simple article for supporting the apparel on the wearer and generally to cheapen such devices so as to bring within the reach of the most modest consumer.

In the drawings Figure 1 is a perspective view of the band and buckle used as necktie holder. Fig. 2 is a plan view of the buckle. Fig. 3 is a longitudinal sectional view of the band and buckle showing the position of the tie in dotted lines.

Referring to the drawings 1 is the eye 35 opening at one end of the thin piece of sheet material, the said material being preferably bent in arc-shape and said eye opening having the saw edge 2 at the inner side thereof forming substantially a part moon-shaped opening adjacent to one end of the piece of material.

3 is a cross slot in the piece of material adjacent to and parallel with the saw edge 2. 4 is a cross slot at the other end of 45 the piece of material corresponding in size to the slot 3, said slot coming out through the piece of material under the outwardly extending lip 5.

6 is the band of elastic material and corresponding in width particularly at the ends thereof to the cross slots 3 and 4, one end of said band being first inserted through the slot 4 from the outer side and then through the eye opening 1 and back over the saw edge 2 and through the slot 3 from the

outer side and then through the slot 4 from the inner side, the free end being loose as shown. Thus when the band is made taut in the buckle the saw edge 2 grips the over fold of the band in the inner side and effectually prevents any slip. 7 is a hook fixedly secured to the other end of the band 6 and adapted to engage in the eye 1.

In the use of this invention particularly, where it is applied as a necktie holder with in double collars the necktie is first inserted between the buckle and band, where the band stretches along the inside of said buckle and looped or tied over the outside of the buckle according to the style of the 70 tie that is to say whether it is a derby or a bow.

The tying of the necktie may be done by the wearer or any one expert in the particular accomplishment, thus it is a hand 75 made knot or bow and may be changed as often as desired. The act of placing it around the neck and over the collar band is very simple and it is here that the invention becomes a great aid to the dresser, 80 for the face of the collar at the front vertical edge is slipped under the lip 5 and the elastic band run around the collar under said face. The collar is then put on in the ordinary way, the hook of the band catching 85 the other vertical edge of the face, therefore as there is nothing more to be done when the wearer has secured his collar on to the shirt than to unhook the band from the edge of the face of the collar and slip 90 it into the opening 1 then the buckle is moved slightly just sufficient to release the lip 5 from engagement with the other vertical edge of the face of the collar and thus each end of the buckle will disappear under 95 the face of the collar and only the tie be in view. In other uses the ornamentation of the buckle is applied in any suitable way either by an ornament rigidly secured to the outer side thereof or a bow tied around 100 in the same fashion as described. The elastic band is secured to the buckle in the same way and may be put around the waist of the wearer, the arm or any other part of the body and secured in the same way.

105 What I claim as my invention is:—

In a buckle and band, a sheet material plate slightly enlarged at each end and having corresponding arc-shaped cuts in the material adjacent to the end edges, the metal 110

inside of one of said cuts being outwardly bent in the form of a lip and the metal inside of the other cut being removed to form a crescent-shaped opening having a serrated inner edge, and a further cross slot parallel with said serrated edge, and a band having a fastener at one end adapted to engage detachably the crescent-shaped opening and removably attached to the plate at

the other end by being threaded through 10 the slots in the manner specified.

Signed at Montreal Que. Canada this fifteenth day of February 1912.

GEORGE EDWARD FIGG.
